US0D1090779S

(12) **United States Design Patent** (10) **Patent No.:** **US D1,090,779 S**
(45) **Date of Patent:** **** Aug. 26, 2025**

(54) **FILTER CAPSULE**

(71) Applicant: **Cytiva US LLC**, Marlborough, MA (US)

(72) Inventors: **Christopher P. Haslam**, Portsmouth (GB); **Neil J. Walker**, Portsmouth (GB); **Charles N. Rothwell**, Portsmouth (GB)

(73) Assignee: **Cytiva US LLC**, Marlborough, MA (US)

(**) Term: **15 Years**

(21) Appl. No.: **29/903,100**

(22) Filed: **Sep. 20, 2023**

(51) LOC (15) Cl. **23-01**

(52) U.S. Cl.

USPC **D23/209**

(57) **CLAIM**

The ornamental design for a filter capsule as shown and described.

DESCRIPTION

FIG. 1 is a bottom isometric view of a filter capsule of the present invention.

FIG. 2 is a top isometric view thereof.

FIG. 3 is a front view thereof.

FIG. 4 is a rear side view thereof.

FIG. 5 is a right side view thereof.

FIG. 6 is a left side view thereof.

FIG. 7 is a bottom view thereof; and,

FIG. 8 is a top view thereof.

The broken lines in the drawings depict portions of the filter capsule that form no part of the claimed design.

1 Claim, 8 Drawing Sheets
